UNITED STATES PATENT OFFICE.

CHARLES ESCHWEI, OF COPIAGUE, NEW YORK, ASSIGNOR, BY DIRECT AND MESNE ASSIGNMENTS, TO MARVEL PRODUCTS COMPANY, INC., A CORPORATION OF NEW YORK.

GASEOUS-FUEL MIXER.

1,119,259.

Specification of Letters Patent.

Patented Dec. 1, 1914.

Application filed October 29, 1913. Serial No. 798,048.

To all whom it may concern:

Be it known that I, CHARLES ESCHWEI, a citizen of the United States of America, and resident of Copiague, in the county of 5 Suffolk and State of New York, have invented certain new and useful Improvements in Gaseous-Fuel Mixers, of which the following is a specification.

This invention relates to mixing devices 10 for fuel for internal combustion engines.

The object of the invention is to provide a device which will very thoroughly mix the vaporized liquid combustible with the air which is also admitted, so that the mixture 15 is supplied in a thoroughly and uniformly mixed condition for combustion, the mixing being so thorough in fact that it is possible not only to employ the customary gasoline, but even to employ a liquid fuel containing 20 a large percentage of kerosene, thus materially reducing the cost of operation of the motor.

The mixing device comprises essentially a wire helix which, by suitable supporting 25 means, is so interposed in the path of the incoming vapor and air fuel mixture as to impart to the same a whirling motion, while simultaneously breaking up the incoming stream.

30 In the accompanying drawing, Figure 1 is a vertical central section of a vaporizer embodying the invention, Fig. 2 is a plan of the device shown in Fig. 1, Fig. 3 is a horizontal section on line 3—3 of Fig. 1, Fig. 4 is a vertical section of a modified form of the device, and Fig. 5 is a horizontal section on line 5—5 of Fig. 4.

Similar reference characters indicate corresponding parts throughout the figures.

40 The vaporizer shown in Figs. 1, 2 and 3 comprises a helix 10 of wire, such for instance as brass wire, which is coiled upon itself, also in the form of a helix, around a center post 11, the lower end of which supports a perforated plate 12 and the upper end of which is provided with an internal screw-thread engaged by a screw 13, whereby the post is attached at its upper end to the top perforated plate 14 of a cylindrical shell 15 made of brass or any other suitable material. The plate 12 is loose at its edge in the shell. The shell is of suitable size to fit within the intake manifold of an 45 internal combustion engine to which the device is to be applied, and is provided at its

bottom with a lateral flange 16 to conform to the size of various manifold flanges. The wire helix may have one or more turns upon itself. In Fig. 1 one turn only is shown, and the overlapping end of the wire is soldered 50 at 17 and 18 to the underlying end of the helix, and the inner end of the helix is itself soldered at 19 to the post 11 near the lower end of the latter. The helix, lower plate 12 and post 11 form thereby one connected whole which may be conveniently withdrawn from the open end of the shell when the screw 13 is released.

55 The mixture of air and vapor fuel from the carburetor that enters the vaporizer at 60 its open end is broken up by the plate 12 into a plurality of small sprays and enters the space in the shell between the two plates 12 and 14; in said space it encounters the helically wound helix of wire and enters 65 into the interior of said helix through the spaces between the convolutions of the same; in its passage into the helix it is broken additionally to the breaking which it receives in passing through the plate 12. The 70 circular form of the convolutions of the helix imparts to the inflowing mixture a whirling motion, that is to say, the streams of mixture are guided by the individual convolutions of the helix during their 75 entrance into the latter in a circular direction, and when they have entered the helix they have this circular motion in a considerable degree, said motion being also a progressive 80 one lengthwise of the helix, following the 85 course of the wire composing the helix. The mixture is thus compelled to travel while whirling in itself helically upward through the helically wound wire helix. Thus, in 90 concurrence with the helically moving current of gas whirling in itself, there is a constant displacement and change in the particles of gas being subjected to that action. These 95 combined movements produced in the gaseous mixture cause such a thorough re- 100 arrangement and redistribution of the particles thereof that the fluid fuel issues from the plate 14 in an exceedingly thoroughly mixed and highly explosive condition; indeed, so thorough is the breaking up and re- 105 mixing of the vapor accomplished, that it is possible to make use as fuel of substances not available for use as fuel in connection with the carburetors and mixing devices heretofore employed. A mixture of 25% of kero- 110

sene with gasolene of the ordinary commercial quality now in use has been found practicable with mixers constructed according to this invention, whereby the cost of operation 5 of the motor is largely reduced over the use of gasolene alone as was heretofore required.

In the modification shown in Figs. 4 and 5, the helix 20, instead of being arranged in 10 helical shape, is arranged spirally for the purpose of reducing the height or thickness of the device as a whole. At suitable points 15 22 the helix is soldered upon itself, so that the spiral form is preserved when the helix is removed from the shell. The whirling motion is attained when the helix is arranged as a flat spiral, but in order to further increase this whirling motion the spiral, at its center, is depressed, as shown 20 at 23. This depression is maintained by at the natural spring action of the helix which, being slightly larger than the internal diameter of the shell 21, causes the center portion of the spiral to be depressed, as shown 25 in Fig. 4, against a convex perforated plate 25 which frictionally engages the shell 21, and thereby retains the spirally wound helix in place. The gaseous mixture enters this device through the plate 25, and all portions 30 of said mixture encounter in their passage the upwardly winding spirally arranged helix. They are thereby given the whirling motion and the travel along the helix which is produced, as before described, by the devices of Figs. 1, 2 and 3, together with the constant exchange of particles produced by the direct flow of the mixture from the intake plate 25 to the outlet plate 24 across 35 the helix. This form of the invention is of 40 special advantage where the available space in the intake manifold of the motor is insufficient to receive the deeper form of the device shown in Figs. 1, 2 and 3.

By the use of the invention the consumption 45 of gasolene is largely reduced and all

the well-known good results attainable only by a more thorough mixture of the fuel, namely, better combustion, less noise and vibration, less carbonizing of the cylinders, and more power and speed from the motor, 50 are attained.

I claim:

1. A gaseous fuel mixer for internal combustion engines, comprising a casing having a perforated top and bottom, and a coil of wire 60 having its convolutions closely adjacent to each other, arranged within the casing and between its top and bottom, said convolutions being arranged in a circular manner between said top and bottom plates, and being at right angles to the top and bottom plates.

2. A gaseous fuel mixer for internal combustion engines, comprising a perforated top plate, a perforated bottom plate, an inclosing support for said top and bottom plates, and a coil of wire having its convolutions closely adjacent to each other, said convolutions being arranged in a circular manner in respect to the center point of the top and 75 bottom plates, and having the largest number of the separate convolutions at right angles to the top and bottom plates.

3. A gaseous fuel mixer for internal combustion engines, comprising a casing having its top and bottom provided with a plurality of perforations, and a coil of wire having a plurality of convolutions arranged closely adjacent to each other and arranged in a circular manner around the center of 80 the plates, each of said convolutions being arranged in a plane vertical to the top and bottom of the casing.

In testimony that I claim the foregoing as my invention, I have signed my name in 90 presence of two subscribing witnesses.

CHARLES ESCHWEI.
